UNITED STATES PATENT OFFICE.

JAMES L. ADAMS, JR., OF WILKINSBURG, PENNSYLVANIA, ASSIGNOR TO WESTINGHOUSE ELECTRIC AND MANUFACTURING COMPANY, A CORPORATION OF PENNSYLVANIA.

ELECTRICAL DISTRIBUTER.

1,075,457.

Specification of Letters Patent.

Patented Oct. 14, 1913.

Application filed November 16, 1911. Serial No. 660,688.

To all whom it may concern:

Be it known that I, JAMES L. ADAMS, Jr., a citizen of the United States, and a resident of Wilkinsburg, in the county of Allegheny and State of Pennsylvania, have invented a new and useful Improvement in Electrical Distributers, of which the following is a specification.

My invention relates to magnetos and other generators that are employed in connection with internal combustion engines to supply current for ignition and other purposes, and it relates particularly to means for distributing the ignition current to the engine cylinders.

The object of my invention is to provide a simple and effective distributor which shall be so constructed as to permit of ready assembling and disassembling of its parts for inspection, adjustment or repair.

My invention is illustrated in the accompanying drawing, Figure 1 of which is a vertical, sectional view through one end of a small generator embodying the same, and Fig. 2 is a view in end elevation of the said generator, a portion of the distributor being shown in section.

The invention is here shown as employed in connection with a small generator of current suitable for ignition or other purposes, and it is actuated by a pinion 1 that is mounted upon one end of the generator shaft 2 and a gear wheel 3 that meshes with the pinion 1. The gear wheel 3 is secured to one end of a short shaft 4 that is rotatably mounted, by means of suitable ball-bearings 5, in the frame 6 of the generator.

Secured upon the outer face of the gear wheel 3 is a circular insulating block 8 in which is embedded a conducting tube 9, the axis of which is inclined to the axis of gear wheel 3 and block 8, and the inner end of which is provided with an exposed extension 10 to form a central contact member upon the outer face of the block 8. The tube 9 serves as a receptacle and guide for a brush 11, a spring 12 for resiliently pressing the brush outwardly being interposed between the inner end of the brush and the bottom 50 of a recess in the block 8 that constitutes an extension of the opening in the tube 9.

The parts just described are inclosed by a cover block 13, that is clamped or otherwise suitably secured to the end face of the gen-

erator frame and is preferably composed of 55 molded insulating material, it being provided with an inclined or frusto-conical inner face against which the outer end of brush 11 bears. Embedded in the cover 13 are a plurality of conductors 14 that are provided at their upper ends with receptacles 15 for plugs 16 and that extend downwardly from the top of the cover, said conductors terminating at their lower ends in enlargements or feet 17 that have uniformly spaced, 65 exposed and inclined contact faces formed flush with the inclined frusto-conical inner face of the cover 13, the said contact faces being interposed in the path of the movement of the brush 11 so as to be engaged in 70 succession thereby during its revolution. Another conductor 18, that is also embedded in the cover 13 and extends downwardly from a receptacle 19 for a plug 19^a, terminates at its lower end, opposite the central 75 contact member 10 carried by the block 8, in a tube 20 that serves as a receptacle and guide for a brush 21, the said brush being caused to resiliently engage the contact member 10 by means of a helical compression spring 22 that is interposed between the inner end of the brush and the bottom end 80 of the tube 20.

In the use of the device, the plug 19^a is connected to the source of supply of ignition 85 current, and the plugs 16 are connected in proper order to the engine cylinders. The current is conducted from the plug 19^a through the parts 18, 20 and 21 to the central contact member 10 upon the block 8 and 90 from thence to the brush 11, which, during its revolution, successively engages and conducts the current to the lower ends of the conductors 14, thus distributing the current to the engine cylinders in the proper sequence.

The present device is peculiar, in that the brush 11 is inclined with respect to its axis of revolution, while the inner face of the block 14 and the lower end faces of the conductors 15 have a corresponding inclination. When the cover 14 is removed from the generator, the brush 11 will be pressed outwardly, but insufficiently, to require manual depression or special attention when it is desired to again apply the cover, as the inclined inner face of the cover is extended sufficiently to engage the end face of the

brush when it occupies its outermost position. Thus, the brush will slide upon the inclined inner surface of the cover and will be pressed inwardly as the cover is applied to the machine and approaches its normal and final position.

I claim as my invention:—

1. A distributor comprising a plurality of spaced terminal members, a revoluble brush, and a pressure spring for said brush, the engaging faces of the brush and of the terminal members being inclined with respect to the axis of revolution of the brush and substantially normal to the force exerted by said pressure spring.
2. A distributor comprising a revoluble brush, and a plurality of spaced terminal members with which the brush is adapted to engage, the brush and the faces of the terminal members that are engaged thereby being inclined with respect to the axis of revolution of the brush.
3. A distributor comprising a rotatable member, a brush carried by the said member and inclined with respect to its axis of

rotation, a cover for the rotatable member having an inclined inner face against which the said brush bears but also extended laterally beyond the brush, and a plurality of spaced terminal members carried by the cover also having inclined faces corresponding to the inclined face of the cover and adapted to be engaged by the brush.

4. A distributor comprising a rotatable member, a brush carried by the said member and inclined with respect to its axis of rotation, a cover for the rotatable member having an inclined inner face against which the said brush bears, and a plurality of spaced terminal members carried by the cover also having inclined faces corresponding to the inclined face of the cover and adapted to be engaged by the brush.

In testimony whereof, I have hereunto subscribed my name this 4th day of Nov. 45 1911.

JAMES L. ADAMS, JR.
